UNITED STATES PATENT OFFICE.

FRED B. KING, OF ALBION, MICHIGAN.

TRIMMING-RAIL FOR CUSHION-SEATS AND SIMILAR STRUCTURES.

1,275,266.

Specification of Letters Patent. Patented Aug. 13, 1918.

Application filed September 20, 1917. Serial No. 192,350.

To all whom it may concern:

Be it known that I, FRED B. KING, a citizen of the United States of America, residing at Albion, in the county of Calhoun and State of Michigan, have invented certain new and useful Improvements in Trimming-Rails for Cushion-Seats and Similar Structures, of which the following is a specification, reference being had therein to the accompanying drawings.

The invention relates to trimming rails such as are used in connection with cushion seats and to which the skirt or facing of the cushion is attached. More specifically, the invention has reference to that type in which a metallic rail, adapted for engagement with the base of the spring frame, is provided with a tacking strip to which the skirt is attached. It is the object of the present invention to obtain a construction of metallic rail or strip which is easily manufactured and conformed to the shape of the seat-frame, and which at the same time provides a tacking strip and a metallic bead for protecting the edge of the fabric tacked to the strip. With certain constructions heretofore used the metallic trimming rail has been provided with an outwardly-extending flange having a beaded edge, the tacking strip being placed in the angle adjacent to said flange so that the beaded edge will form a protection for the edge of the fabric attached to said strip. The objection to such constructions is that the outwardly-extending flange so stiffens the strip that it is difficult to bend the same into conformity to the shape of the seat frame. On the other hand, where the flange is omitted there is nothing to protect the edge of the fabric from wear. I have therefore devised a construction in which the rail is unflanged so as to permit of readily bending, but is provided with a wire strip adjacent to the outer face of the tacking strip for forming the fabric protection.

My co-pending application Serial No. 193,654 filed Sept. 28, 1917, for trim rail for cushion seats and other upholstery claims some of the features disclosed in this application,

In the drawings:

Figure 1 is a sectional perspective view of a portion of the rail;

Fig. 2 is an enlarged cross-section thereof;

Fig. 3 is a similar view showing a modified construction;

Fig. 4 is a similar view showing still another modification;

Fig. 5 is a side-elevation of the rail showing the manner of attaching the facing or skirt thereto; and

Fig. 6 shows another modification.

A is a flat metallic strip, preferably provided at its lower edge with a bead B and also preferably provided with struck-out portions C on its inner face for attachment to the base of the spring frame. D is the tacking strip, preferably formed of wood, and which is secured to the outer face of the rail A with its lower edge adjacent to the top of the bead B. The tacking strip D may be secured by any suitable means, such as the struck-out lugs E and F, shown respectively in Figs. 2 and 3, or by the rivets G shown in Fig. 4.

To protect the edge of the fabric which is secured to the tacking strip I provide a metallic strip, preferably a wire H, which is arranged to extend along the lower edge of the outer face of said tacking strip and is secured to the rail A. As shown in Figs. 1 and 2 this wire H is secured by a tongue or clip I struck out from a portion of the clip E which secures the strip D. The wire is thus clamped between the outer face of the portion E and the inner face of the portion I. In Fig. 3 a modified construction is shown, where the tongue or clip F is formed with a return bend J therein for embracing the wire H, the portion K above said bend serving to hold the strip D. In Fig. 4, a clip L formed of a separate piece of sheet-metal is secured by the rivet G which attaches the strip D to the rail A, and this clip L is formed with a return bend M for embracing the wire H and a portion N extending inward above the bead B. With each of these constructions when the skirt or facing O is attached to the rail it is drawn down adjacent to the wire H and is then

cut off, said wire forming a bead for protection therefor.

It will be understood that in bending the trimming rail into conformity to the shape 5 of the seat to which it is applied, the wire H will not interfere with said bending, as would be the case with a beaded flange.

In the modified construction shown in Fig. 6, the tacking strip D is secured by the 10 wire H anchored by the tongues N' and tongues P embracing the opposite edge of the strip and struck-out from the metallic strip A.

What I claim as my invention is:

15 1. The combination with a trim rail having a tacking strip attached thereto, of a wire secured adjacent to said tacking strip forming a protecting bead for the fabric tacked thereto.

20 2. The combination with a trim rail and a tacking strip secured thereto, of a wire extending along the outer face and lower edge of said tacking strip, a clip for securing said tacking strip to said rail, and 25 means upon said clip for securing said wire thereto.

30 3. The combination with a trim rail and a tacking strip secured thereto, of a wire extending along said tacking strip, and a clip for securing said tacking strip to said rail having a return bend therein for securing said strip.

4. The combination with a trim rail and a tacking strip secured thereto, of a wire extending along said tacking strip, and a clip struck out from said rail for securing said wire. 35

5. The combination with a trim rail and a tacking strip secured thereto, of a wire extending along said strip, and a clip struck out from a portion of said rail, forming a common means for securing said tacking strip and wire. 40

6. The combination with a trim rail and a tacking strip secured thereto, of a wire extending along said strip, and a clip struck out from a portion of said rail having an angle flange for securing said tacking strip and a return bend for securing said wire. 45

7. The combination with a trim rail and a tacking strip secured thereto, of a wire extending along said tacking strip, a clip struck out from a portion of said trim rail, bent to embrace said tacking strip, and a portion struck out from said clip bent to embrace said wire. 50

8. A trim rail, comprising a metallic strip, a tacking strip lying adjacent thereto, a wire extending along said tacking strip, forming a protecting bead for the fabric attached to said strip, and means for securing said wire and tacking strip to said metallic strip. 55

In testimony whereof I affix my signature.

FRED B. KING.
